UNITED STATES PATENT OFFICE.

FRANK H. STOLP, OF CHICAGO, ILLINOIS.

RADIATOR-TUBING.

No. 877,252.

Specification of Letters Patent.

Patented Jan. 21, 1908.

Application filed September 29, 1904. Serial No. 226,485.

To all whom it may concern:

Be it known that I, FRANK H. STOLP, a citizen of the United States, residing at Chicago, county of Cook, State of Illinois, have invented

5 a certain new and useful Improvement in Radiator-Tubing, and declare the following to be a full, clear, and exact description of the same, such as will enable others skilled in the art to which it pertains to make and use the 10 same, reference being had to the accompanying drawings, which form a part of this specification.

My invention relates generally to heat radiators, and more particularly to devices for 15 dissipating the heat of and thereby cooling a circulating fluid.

It is necessary that the cylinders of engines, especially of the explosive type, should be surrounded by a jacket between which and 20 the cylinder a cooling fluid circulates to absorb the heat generated in the cylinder and prevent the latter from becoming unduly heated. In order that the heat absorbed by the fluid may be dissipated the fluid circulates through a cooling device, such for instance as a radiator, by means of which the 25 temperature of the fluid is so reduced that when it returns through the jacket it again absorbs heat from the cylinder. A form of 30 radiator in common use for automobiles consists in a tube communicating with the water jacket and provided with a number of coils preferably located at the front of the vehicle, the coils being surrounded by projecting 35 points or flanges for radiating the heat.

The primary object of my invention is to provide radiating coils of the type referred to with improved radiating surfaces which will quickly dissipate the heat and thereby greatly 40 lower the temperature of the fluid as it passes through the radiator.

A further object of my invention is to provide improved tubing for radiator coils which will be simple in construction, inexpensive in 45 manufacture and efficient in use.

My invention generally described consists in a radiating tube the exterior surface of which is surrounded by coiled wire, spirally wound around the tube, the convolutions of 50 the adjacent turns of the coiled wire overlapping, and means for securing the coiled wire around the tube.

My invention will be more fully described hereinafter with reference to the accompanying drawing in which the same is illustrated 55 as embodied in a convenient and practical

form, and in which the figure is a longitudinal sectional view, one turn of the coiled wire and a portion of the tube being shown in elevation.

Reference character A³ indicates a tube made of any suitable metal through which the cooling fluid is adapted to flow from the water jacket around the cylinders of an explosive engine.

B³ designates a coiled wire, the convolutions of which are wedge-shaped. The coiled wire is wound spirally around the tube A³ and is secured thereto in any suitable manner, such for instance as by brazing. In 70 order to render the connection of the coiled wire with the tube more secure a tie wire C³, is preferably located within the convolutions of the coiled wire and drawn tightly around the tube.

By forming the convolutions wedge-shaped an extended engagement with the tube is secured, while the radiation of heat is promoted owing to the convolutions being tapered outwardly. The convolutions of adjacent turns of the coiled wire overlap thereby increasing the number of turns of coiled wire which it is possible to wind around a given length of tube. The overlapped portions of the convolutions also serve to give 85 greater rigidity and strength to the structure.

A retaining wire c³ is preferably wound around the coiled wire between the convolutions of the adjacent turns, thereby strengthening the convolutions and preventing their 90 becoming bent or flattened against the tube.

My improved radiator tubing may be used in any form of radiator, or wherever it is desired to dissipate the heat from a fluid but is particularly designed for use in the manufacture of radiators for automobiles.

From the foregoing description it will be observed that I have invented an improved tubing for radiators which affords a large extent of radiating surface and is thereby capable of quickly lowering the temperature of a fluid passing through the radiator.

Having now fully described my invention what I claim as new and desire to secure by Letters Patent is:

1. The combination with a radiator tube, of a coiled wire spirally wound around and secured to the tube, the convolutions of adjacent turns of the coiled wire being overlapped.

2. The combination with a radiator tube, of a coiled wire spirally wound around the

tube, the adjacent convolutions of the wire being over-lapped, and a retaining wire within the convolutions of the coiled wire for securing the same to the tube.

5 3. The combination with a radiator tube, of a coiled wire spirally wound around the tube, the convolutions of adjacent turns of the coiled wire being over-lapped, means for securing the coiled wire to the tube, and a tie

wire surrounding the coiled wire between the 10 convolutions of the adjacent turns thereof.

In testimony whereof, I sign this specification in the presence of two witnesses.

FRANK H. STOLP.
